Geo. P. Kimmel. ATTORNEY.

UNITED STATES PATENT OFFICE.

MANUEL FELDMAN, OF NEW YORK, N. Y.

MAT.

Application filed August 14, 1925. Serial No. 50,293.

This invention relates to mats, and has for its object to provide, in a manner as hereinafter set forth, a strong and durable mat which not only possesses a highly and distinctive decorative function, but also a protecting function when used upon table tops, table cloths, etc., to prevent the passage of heat or moisture thereto, and further a mat that can be used under plates, platters, dishes, cups and saucers, glasses, breakfast tea, luncheon and dinner services, flower pots, jardinières, candle sticks, console, Mah jongg and card sets, bric-a-brac, upon table tops generally, and as a decorative wall panel.

A mat in accordance with this invention, is constructed from a plurality of shaped lengths of braid, tape or other ribbon like material standing on edge and of the desired width. The braid, tape or ribbon is herein-after generally referred to as braid. The shaped lengths of braid are termed units and secured together to form the mat body. The braid preferably used in the construction of the units is the fine straw braid employed in the manufacture of women's hats, but it is to be understood that any material capable of being employed to provide a mat in accordance with this invention can be used.

As illustrating one of the forms of mats made by the method, in accordance with this invention, reference is had to the accompanying drawing, in which

Figure 1 is a plan of the mat.

Figure 2 is an edge view thereof.

Figures 3 and 4 are respectively sections on lines 3-3 and 4-4 Figure 1.

Figure 5 is a fragmentary view in side elevation of a braid.

Referring to the drawing A generally indicates the mat body consisting of a series of individual units each formed from a shaped braid. The units forming the mat body are indicated at 1 to 21, both inclusive. The individual units are of convolute form. The units are arranged in sidewise, endwise and enclosing positions relative to each other. Each unit is secured together by stitching 22 and the units when arranged relatively to each other in the manner as aforesaid are secured together by stitching 23. The stitching 22 can also be used as a means for not only securing a single unit together, but also several units. The securing of a unit together maintains its faces in opposed abutting arrangement. A sample of the pre-

ferred braid employed is indicated at 24, Figure 5, and which consists of the fine straw braid used in the manufacture of women's hats.

It is to be understood that the drawing illustrates but one of the many designs of mats made in accordance with this invention, and that the mat consists of a plurality or series of independent units, each formed from a length of braid arranged in a manner to bring its faces into contact. The independent units are then assembled in sidewise or endwise contact. Each of the units can be of a different shape, as well as certain of the units enclose or extend between or be positioned against ends of other of the units. After the units are arranged in sidewise or endwise contact they are secured together by stitching or cementitious material or other suitable means, but preferably by stitching.

The braid is so rolled, spiralled, folded or otherwise assembled through sewing (or other similar processes) as to bring its faces in close contact, thus forming small areas or independent units, which present smooth upper and lower surfaces. The upper and lower surfaces are really made up of the exposed edges of the braid.

To set forth the types of such independent units attention is directed to the following:

Discs which are made by winding the braid in spiral form in much the same fashion as narrow ribbons are wound on pill box disc spools. Viewed from the top these discs show merely the edges of the material used while on the side the width or face of the material appears. These adjacent faces are fastened to one another by means of stitches, adhesives or other means which will serve to hold each convolution in close contact with the adjacent convolutions.

Triangles are made in the same manner. Naturally squares, pentagons, hexagons and other polygons are variations already successfully employed in these mats. There are also ovals, ovoids, and countless other irregular shapes constructed in a similar manner, sometimes being formed by successive windings in spiral fashion and sometimes being formed by zig-zag foldings. By zig-zag foldings is meant the processes of bending the braid transversely first one way and then the other and bringing the sides or surfaces of the material so bent into close contact with one another. In the zig-zag form of convolution, the faces of the braid are fastened

one to the other in the same manner as in the spiral forms.

While each of these units may be made from one continuous piece and color of braid 5 they may also be made of more than one piece each of a different color, thus forming decorative effects. Likewise, two or more pieces of braid of the same or different colors may be joined together and wound 10 or zig-zagged as though they were a single piece.

In constructing mats from these independent units, the mat may be made from either one unit or from a number of units 15 assembled together. In the former case the mat may be one color or may present two or more colors depending upon the number of pieces of braid used, and the colors of these pieces, or depending upon the finishing 20 decorations which may be applied to the surface after the unit is complete.

In the second case the two or more independent units are assembled together by bringing into contact the narrow faces of 25 the braid which now form the edges of the independent units and by fastening the independent units so assembled in contact by means of stitches, adhesives, or other means. The shapes into which the various independent 30 units may so be assembled are limitless, the main types being the oblong, the oval and the disc.

Where regular geometric polygons are used 35 for the independent units, the method of assembling can follow the form of assembling tiles, each unit being closely attached to surrounding units. In other cases where the figures are irregular, an open-work effect 40 may result at points where the units do not come into close contact. Sometimes small units are wound and fastened in spiral or zig-zag fashion, and inserted to fill these apertures.

Naturally depending upon the character 45 of the units forming the assembly, the edges of the mats may form straight lines, smooth curves, or may present a scalloped, toothed or irregular edge.

As a result of the varying colors of the 50 independent units thus assembled, and the designs thus formed, mosaic effects can be achieved.

In some types of these mats, flowers, butterflies, and other such objects can be made 55 in the manner described by assembling small independent units of various colors representing petals, centers, stems, leaves, etc., or wings, antennæ, etc., respectively. In such cases the shape of the mat is often a 60 silhouette of the form depicted. In other cases the floral decorations, butterfly decorations, bird decorations, etc., are inserted in-

to the main field of the mat, in mosaic fashion.

In addition to the various ornamental and decorative effects attained by means of assembling these independent units of varying colors, the flat surfaces of the finished mats may also be decorated by painting, etc.

Among the many other advantages, the unusual and unique construction of these mats results in a durable structure, since the edges of the braid are presented for wear instead of the faces.

Due to the unique winding or zig-zagging 75 of the braid in concentric convolutions, or parallel configurations, etc., a highly lustrous sheen appears on the surface of these mats in much the same manner and much the same way as the sheen appearing on 80 spooled silk thread, or brushed metal, or a beaver hat.

Due to the tiny air spaces in the construction, and due to the thickness of the mat, and due to the fact that the braid rests on edge, 85 the entire assembly acts as a poor conductor of heat. This is particularly important when the mats are used for hot plate purposes.

Although the method is designed primarily for the manufacture of mats, yet it is obvious that it also applies to the production of rugs, as the difference resides solely in the sizes of the respective products.

What I claim is:

1. A covering comprising a plurality of body units each formed of a length of braid bent in convolute form and having the faces thereof abutting and the edges thereof forming the upper and lower faces of the unit, 100 means for securing the braid of each unit in shaped position, and independent means for securing units together in lateral opposed relation to form a mat body.

2. The process herein described of making 105 a covering, said process consisting in coiling braid so that the coils will be arranged side by side; uniting the convolutions of the coil by transverse threads extending from one edge of the section to the other at an angle to the line of the braid; and assembling the sections to form a rug.

3. As a new article of manufacture, a 110 covering made up of a series of sections connected together by stitching, each section consisting of a length of braid arranged on edge and threaded back-and-forth to form a section of a given design, the braid of each section being secured by a series of transverse stitches.

In testimony whereof, I affix my signature hereto.

MANUEL FELDMAN.
